BARBECUE

Walter Koziol, Russell, Ill., assignor to Charmglow Products, Inc., Antioch, Ill., a corporation of Illinois

Filed Oct. 21, 1965, Ser. No. 87,668

Term of patent 14 years

(Cl. D81—10)

Fig.1

The handle shown in broken lines in FIGS. 1, 2 and 3 is included for illustrative purposes only.

What is claimed is:

The ornamental design of a barbecue, substantially as shown and described.
